Attorney.

UNITED STATES PATENT OFFICE

WILLIAM O. ISAACSON, OF CHICAGO, ILLINOIS

FASTENER

Application filed November 15, 1928. Serial No. 319,712.

This invention relates to clips or fasteners, and with regard to certain more specific features to fasteners for building construction and the like.

5 Among the several objects of the invention may be noted the provision of fastening means adapted to be applied directly to concrete, gypsum and like hard surfaces directly by means of blows and without other complicated movements; the provision of an article of manufacture of the class described which is delivered to the user with the fastening means assembled and set for driving; and the provision of a device of the class described 10 which is applicable to the device to which it is fastened with a minimum of complication. Other objects will be in part obvious and in part pointed out hereinafter.

The invention accordingly comprises the 20 elements and combinations of elements, features of construction, and arrangements of parts which will be exemplified in the structure hereinafter described, and the scope of the application of which will be indicated 25 in the following claims.

In the accompanying drawings in which is illustrated one of various possible embodiments of the invention,

Fig. 1 is a plan view of a form of the invention adapted to hold metal corner beads in place;

Fig. 2 is a side elevation of Fig. 1;

Fig. 3 is a plan view showing the device of Figs. 1 and 2 applied to a metal corner bead;

Fig. 4 is a cross section taken on line 4-4 of Fig. 3; and

Fig. 5 is a layout showing the economical manner in which the devices shown in Figs. 1 to 4 are manufactured.

Similar reference characters indicate corresponding parts throughout the several views of the drawings.

Referring now more particularly to Fig. 1, there is illustrated at numeral 1 a blank composed preferably of sheet metal having a more or less rectangular body portion 3 and a finger 5, the body portion and finger being so symmetrically shaped that they may be stamped from a single strip in the nested arrangement illustrated in Fig. 5. As will be

seen from said Fig. 5, the shaping is arranged to eliminate all waste of material, the cut-out portion on each side of each finger comprising one-half of the space required for shaping the finger on an adjacent nested blank. The body portions are arranged along each side of the strip in staggered arrangement.

Each blank 1 is provided at its body portion 3 with up struck tongues 7 and 9, one of which tongues 7 is open in a direction opposite to the opening of the other tongue 9. The open ends of the tongues are each provided with bent up portions 11 for facilitating application of the device. It will be seen by reference to Fig. 3 that corner beads 13, such as are used in plastering construction and the like have edges 15 and suitable openings 17, so that by suitably positioning the blank 1, the tongue 9 may be hooked into one of the openings 17 and the tongue 7 hooked under an edge 15.

Heretofore with structures of this class, there have only been openings such as nail holes provided for the fasteners or the like 75 which are to go through them, the fasteners being delivered to the user separately. Sometimes not even nail holes were provided. After getting the blank 1 into the position above described, on the corner bead, the user 80 was required to hold the blank and apply a nail or the like through the opening, all with one hand, so that the other hand, holding a hammer or the like, might be used to drive home the fastening nail or the like. The result was that fingers were often injured because of the necessity for doing three things 85 with only two hands.

I have overcome the above difficulties by providing the fingers 5 with pressed-out, 90 hollow domes or cones 19, each having an opening 21 at its apex for the purpose of snugly receiving a nail 23. It will be appreciated that the openings 21 may be made somewhat smaller than the nails so that the latter may at the point of manufacture be driven partially home (preferably automatically), so as to remain assembled and snugly fitting in the openings. The metal 27 which rolls down, due to fastening the nails in 100

their domes does not interfere with a flat placement of the fastener against the wall 25 to which it is fastened (see Fig. 4).

Returning to Fig. 3, it will be seen that after hooking the fastener to the bead by means of the tongues 7, 9, all that is necessary for final fastening is that the device be held somewhere at a distance from the nails 23 by one hand and said nails be given blows with a hammer, inasmuch as they have already been positioned in the blank 1 at the point of manufacture and are ready for driving.

Hence only two operations are required which may be performed by two hands. An 15 advantage is that the nails are held in a more rigid position than when held by hand which is desirable where concrete or the like is being driven into. The fingers are also out of the way of the blows being struck.

20 Another advantage of a corner bead clip of this type rests in the ease with which it may be attached to the corner bead and nailed to the concrete. In the course of erection of corner beads it will eliminate the tedious operation of fastening the nails through the corner bead clip, as well as the danger of striking finger tips in the attempt to start and to drive the comparatively short, stub 25 nails used for this purpose.

30 The nails 23 are composed preferably of hardened material, adapted to be driven without bending directly into hard and brittle materials such as concrete or gypsum. The domes not only provide a recess for the 35 rolls of metal 27 but aid in holding in the chips of concrete and the like which would otherwise fly out and be lost, thereby aiding the nails in obtaining a sure grip. The final blow somewhat depresses the dome and compresses any loosened material so as to aid in holding the nail. The rolls of metal 27 also 40 provide somewhat of a cylinder in which the nails are better gripped than if they passed through a clean cut opening. It will be noted 45 from Fig. 2 that lateral serrations 29 aid in holding the nails in their assembled positions ready for driving. Fig. 2 shows the one-piece assembly as delivered to the user.

50 It will be seen that the advantages of the invention include the nails assembled in the dome, the nesting features for economical manufacture and the automatic stop feature, effected when the bottoms of the tongues 7, 55 9 are reached upon turning the device upon the corner bead.

In view of the above, it will be seen that the several objects of the invention are achieved and other advantageous results attained.

60 As many changes could be made in carrying out the above constructions without departing from the scope of the invention, it is intended that all matter contained in the 65 above description or shown in the accom-

panying drawings shall be interpreted as illustrative and not in a limiting sense.

I claim:

1. A clip fastener for corner beads comprising a body portion, oppositely opened 70 struck up tongues formed in said body portion, a finger extending from the body portion, at least one dome formed in the finger, an opening in the dome and fastening means assembled and snugly fitting in said opening. 75

2. A clip fastener for corner beads comprising a body portion, oppositely opened struck up tongues formed in said body portion, a finger extending from the body portion, at least one dome formed in the finger, 80 an opening in the dome and fastening means assembled and snugly fitting in said opening, said finger being so formed with respect to the body portions as to leave adjacent space of a shape comprising one-half of the finger 85 shape.

3. A clip fastener for corner beads having openings, comprising a body portion, oppositely disposed holding tongues formed in said body portion adapted to engage said 90 openings, an extension from the body portion, said extension having at least one opening, fastening means associated with said opening and means associated with the opening for snugly holding said fastening means 95 in assembly.

In testimony whereof, I have signed my name to this specification this 10th day of November, 1928.

WILLIAM O. ISAACSON.
